(57) **CLAIM**

The ornamental design for a vehicle door storage unit, as shown and described.

DESCRIPTION

FIG. 1 is a front-top perspective view of a vehicle door storage unit showing my new design;

FIG. 2 is a front-bottom perspective view thereof;

FIG. 3 is a rear-top perspective view thereof;

FIG. 4 is a rear-bottom perspective view thereof;

FIG. 5 is a front elevational view thereof;

FIG. 6 is a rear elevational view thereof;

FIG. 7 is a left elevational view thereof;

FIG. 8 is a right elevational view thereof;

FIG. 9 is a top plan view thereof;

FIG. 10 is a bottom plan view thereof; and,

FIG. 11 is a supplemental view of the vehicle door storage unit in a folded configuration.

The broken lines shown are for illustrative purposes only and form no part of the claimed design.
